UNITED STATES PATENT OFFICE.

HANS OLOF LINDGREN, OF STOCKHOLM, SWEDEN, ASSIGNOR TO AKTIEBOLAGET
SEPARATOR, OF STOCKHOLM, SWEDEN.

LUBRICATING DEVICE FOR TURBINE-DRIVEN CENTRIFUGAL MACHINES.

1,253,400.

Specification of Letters Patent. Patented Jan. 15, 1918.

Application filed December 28, 1915, Serial No. 68,986. Renewed November 2, 1917. Serial No. 200,000.

To all whom it may concern:

Be it known that I, HANS OLOF LINDGREN, a subject of the King of Sweden, residing at Stockholm, Sweden, have invented certain new and useful Improvements in Lubricating Devices for Turbine-Driven Centrifugal Machines, of which the following is a specification.

In the dairy industry centrifugal cream separators are used, which are directly driven by means of steam turbines. The steam exhausted from said turbines is usually utilized for heating or pasteurizing the milk to be separated. In order, however, that this may take place without inconvenience, it is necessary that the exhaust steam be so far as possible free from oil particles, which, when present, are deposited on the heating surface of the pasteurizer and thereby interfere with the transmission of heat across the walls of same.

The present invention relates to an improvement, whereby an effective and economical lubricating of the different parts of the machinery is effected. At the same time the invention provides an apparatus of such construction that oil particles will not be drawn off with the exhaust steam.

The nature of the invention will more fully appear from the following detailed description thereof, with reference to the accompanying drawing, which illustrates schematically the lower part of a turbine driven cream separator with the appendant frame—and bearing devices in vertical cross-section. *a* is the turbine disk, which is mounted on the driving spindle *b*. This latter is at the upper end guided by the bearing *c* and at the lower end by the bearing *d*. *e* is a bottom screw, which takes up the weight of the rotating parts and eventually other downwardly acting powers. In the bearing *c* a bushing *f* is inserted to which oil is conducted in a suitable manner and from whose lower end the same flows into a chamber *g*.

In the bottom of said chamber a bushing *h* preferably made of Babbitt's is inserted, leaving a small annular space between itself and the bowl spindle *b*. Beneath the said bushing *h* there is another chamber *i*, in the bottom of which also a bushing *f* is inserted not quite closely surrounding the spindle. The chamber *i* is by means of a pipe *k*

connected with the free air, and consequently 55 the air pressure in the air chamber *i* is equal to the surrounding air pressure. The chamber *g* is by a pipe *l* connected with the chamber *m* surrounding the lower end of the bowl spindle and the top of the bottom 60 screw *e*. The bearing *d* is provided with a bushing *n*, and above said bushing there is a chamber *o* formed in the wall of the bearing. This chamber is at the upper side covered by a bushing *p* not quite closely surrounding the bowl spindle. The chamber *o* is by means of the pipe *q* in communication 65 with the air, so that the atmospheric pressure always prevails in the said chamber.

The function of the above described device 70 is as follows:

The oil escaping from the bushing *f* is collected in the chamber *g*, from which the same passes through the pipe *l* into the chamber *m*. As atmospheric pressure always prevails in the chamber *i* there is no liability of the oil being sucked into the turbine house, in case a vacuum should be produced in the said chamber, nor will the oil be prevented from running into the chamber *g*, if an overpressure should arise in the 75 turbine house.

It is to be noted, that the bushings *h* and *i* do not closely surround the spindle. Consequently by a rising pressure a small 80 quantity of steam enters the chamber *i*, and by a decrease of pressure a small quantity of air enters the turbine house through the annular space between the bushing *j* and the spindle, but this has no influence upon 85 the flowing of the oil into the chamber *g* nor on the conducting of same into chamber *m* through pipe *l*. As soon as the oil has filled up the said chamber *m*, the same rises inside the bushing *n* into the chamber *o* 90 from which it escapes through pipe *q*. By prevailing over-pressure in the turbine house a small quantity of steam enters into the chamber *o* through the annular space between the bushing *p* and the spindle, and 95 by vacuum a small quantity of air is sucked through pipe *q* and the chamber *o* into the turbine house, this having no influence on the lubricating of the bushing *n*, as on the upper surface of same the atmospheric pressure always prevails.

By the above described device it thus transpires that although no close fit between

the bowl spindle and the bottom and cover of the surrounding turbine house is necessitated, full security is gained, that the lubricating of the parts takes place in the 5 desired manner and independent of eventually prevailing over- or underpressure in the turbine house, and in addition thereto the oil is prevented from being drawn off with the steam.

10 The above described lubricating device may be modified in this way, that the oil is not conducted from chamber *g* into chamber *m*, but instead thereof into chamber *o*, whereby, of course, the pipe *q* communicating with the atmosphere might not lead 15 from the bottom of the said chamber. In this case the oil sinks down through the bushing *n* into the chamber *m*, lubricating the top *e* of the bottom screw, whereafter 20 the same is drawn off from the said chamber.

What I claim is:—

1. In steam turbines for driving centrifugal machines, a turbine housing, bearing bushings in the top and bottom of the housing, a spindle passing through said bearing bushings, and means for lubricating said bushings and said spindle independently of the existing pressure in the turbine housing.

2. In steam turbines for driving centrifugal machines, a closed turbine housing having upper and lower oil-receiving chambers, a top bearing bushing above the upper oil-receiving chamber, a bottom bearing bushing above the bottom oil chamber, a driving 35 spindle rotatably mounted in said bushings, a turbine wheel mounted upon said spindle, and means for preventing the pressure existing in the turbine housing from interfering with the oil supply to said bearing bushings.

40 3. In steam turbines for driving centrifugal machines, a closed turbine housing provided with a plurality of upper chambers and a plurality of lower chambers, a top bearing bushing above said upper chambers,

45 a restricted communicating passage between said upper chambers, a communicating passage being provided between said upper chamber and the interior of said turbine housing, a bearing at the bottom of said lower chambers, a bearing bushing between

50 said lower chambers, a communicating passage being provided between one of said lower chambers and the interior of said turbine housing, one of said upper chambers

55 and one of said lower chambers having air vents, a driving spindle mounted in said bushings, a turbine wheel mounted on the driving spindle, and means for conveying lubricating fluid from one of said upper 60 chambers to one of said lower chambers; substantially as described.

65 4. In steam turbines for driving centrifugal machines, in combination, a driving spindle, a turbine wheel mounted on said spindle, a closed turbine housing for the

turbine wheel, a lubricating top bearing bushing surrounding said spindle, said housing being provided with an oil-collecting chamber beneath said bushing and with a second chamber beneath said oil-collecting 70 chamber, said second chamber communicating with the oil-collecting chamber and with the open air and also communicating with the turbine housing, a bottom bearing bushing, said housing being also provided with a 75 chamber beneath said bottom bearing bushing, which chamber communicates with the upper oil-collecting chamber, and said housing being provided with a chamber above said bottom bearing bushing for collecting 80 the oil mounting through the lower bushing, said collecting chamber being connected with the open air and with the interior of the turbine housing; substantially as described.

5. In steam turbines for driving centrifugal machines, a turbine housing, top and bottom bearing bushings, a spindle passing through said bearing bushings, a turbine wheel mounted on the spindle, and means for lubricating said bushings and said spindle 90 independently of the existing pressure in the turbine housing and for preventing the entrance of lubricating fluid into said housing.

6. In steam turbines for driving centrifugal machines, in combination, a turbine housing, a top bearing bushing, a bottom bearing bushing, said housing having an air-vented chamber below said top bearing bushing and having a second air-vented chamber 100 above the lower bearing bushing, a restricted passage being provided from the interior of the housing to each of said air-vented chambers, an oil chamber being provided between the upper bearing bushing and the upper air-vented chamber and having restricted communication with said air-vented chamber, an oil chamber being provided below the bottom bearing bushing and means connecting the last-named oil chamber with the 110 upper oil chamber.

7. In steam turbines for driving centrifugal machines, in combination, a closed turbine housing, an upper bearing bushing, a lower bearing bushing, a shaft mounted in 115 said bushings, a turbine-wheel upon said shaft, a bushing loosely surrounding said shaft and spaced beneath said upper bearing bushing to form an air-vented chamber, and a bushing loosely surrounding said 120 shaft and spaced above said lower bearing bushing to form a second air-vented chamber.

8. In steam turbines for driving centrifugal machines, in combination, a closed turbine housing, an upper bearing bushing, a lower bearing bushing, a shaft mounted in 125 said bearing bushings, a turbine-wheel upon said shaft, a bushing spaced beneath said upper bearing bushing and loosely surround- 130

ing said shaft, an air-vented chamber being provided between said upper bearing bushing and said loose bushing, said air-vented chamber communicating with the interior of the housing, a bushing spaced above said lower bearing bushing and loosely surrounding said shaft, an air-vented chamber being provided between said lower bearing bushing and said loose bushing, said air-vented chamber communicating with the interior of the housing.

9. In steam turbines for driving centrifugal machines, a turbine housing, top and bottom bearing members, a spindle passing through said bearing members, a turbine wheel mounted on the spindle, and means for preventing the pressure existing in the turbine housing from interfering with the supply of lubricant to said bearing members.

10. In steam turbines for driving centrifugal machines, in combination, a turbine housing, a plurality of bearing members, a spindle mounted in said bearing members, a turbine wheel on the spindle and means for preventing the pressure existing in the turbine housing from interfering with the supply of lubricant to said bearing members.

11. In steam turbines for driving centrifugal machines, in combination, a closed turbine housing, an upper bearing bushing, a lower bearing bushing, a shaft mounted in said bushings, a turbine wheel upon said shaft, said housing being provided with an air-vented chamber below said upper bearing bushing and a second air-vented chamber above said lower bearing bushing, each of said chambers communicating with the

interior of the turbine housing through annular passages surrounding said shaft.

12. In a steam-driven centrifugal machine, a turbine housing containing a turbine wheel chamber, a pair of bearings one of which is above and the other below said chamber, a spindle mounted in said bearings, a turbine wheel mounted on said spindle, said housing being provided with an air-chamber between each bearing and the turbine wheel chamber, each of said air-chambers being provided with passages communicating with the external atmosphere, and means between each air-chamber and the turbine wheel chamber for providing restricted passages between these chambers.

13. In a steam-driven centrifugal machine, a turbine housing containing a turbine wheel chamber, a pair of bearings one of which is above and the other below said chamber, a spindle mounted in said bearings, a turbine wheel mounted on said spindle, said housing being provided with an air chamber between each bearing and the turbine wheel chamber, each of said air-chambers being provided with passages communicating with the external atmosphere, and each of said chambers communicating with the interior of the turbine housing through restricted passages.

In testimony whereof I affix my signature in presence of two witnesses.
